UNITED STATES PATENT OFFICE.

GOTTHILF ANSGARIUS BETULANDER, OF STOCKHOLM, SWEDEN, ASSIGNOR TO THE RELAY AUTOMATIC TELEPHONE COMPANY, LIMITED, OF LONDON, ENGLAND.

TELEPHONE SYSTEM.

Application filed March 1, 1923. Serial No. 622,090.

To all whom it may concern:

Be it known that I, GOTTHILF ANSGARIUS BETULANDER, a subject of the King of Sweden, and resident of Sodertorns Villastad, Stockholm, Sweden, have invented new and useful Improvements in Telephone Systems, of which the following is a specification.

This invention relates to automatic and semi-automatic telephone systems of the kind in which lines and switching apparatus are brought together by groups in switching divisions, in which the selection of a disengaged outgoing junction line is effected by means of a number of non-numerical selectors or so called searchers (otherwise known as master switches) which are separate from the connecting apparatus, and accessible in common to the incoming lines. In some systems of this kind, particularly those in which the connections are established by means of relays, means have been provided for preventing double connections and confusion of lines, by which means when there are several simultaneous calls, the different calls in each particular switching division become effective in succession, so that only one calling line can obtain connection at a time, in which case, therefore, only one searcher is required for each switching division. This arrangement, however, has the disadvantage that a whole switching division and, consequently, also all incoming lines of the division may be blocked by faults in said common switching apparatus. When grouping the lines in large groups it therefore becomes a practical necessity to provide means which, while allowing simultaneous connection of several calling lines in the same switching division, will prevent double connections. This is attained according to the present invention by putting the marking of the different lines in the connecting apparatus under the control of the searchers, of which in this case there are several in each switching division, so that, when there are simultaneous calls, the lines to be connected will be marked simultaneously and separately in different connecting apparatus.

The invention is illustrated by the accompanying drawings, in which Figs. 1, 2 and 3 illustrate schematically the principle of

the invention, while Figs. 4, 4^A and 5 show a complete circuit diagram of an arrangement according to Fig. 3, only two searchers being, however, shown in these latter figures.

Fig. 1 shows schematically a switching division comprising a number of incoming lines IL and a number of outgoing lines UL. The circles at the points of intersection of these lines indicate the connecting possibilities and the rectangles AK indicate the connecting apparatus, which in the example shown are supposed to be assigned to the outgoing lines, so that each outgoing line may obtain by means of an appertaining apparatus connection with any one of the incoming lines. The connecting apparatus may, however, be allotted to the incoming lines. The particular construction of the connecting apparatus is unessential for the present purpose.

The incoming lines IL are provided with a number of searchers S₁, S₂ accessible in common to the incoming lines, two of said searchers being shown in Fig. 1, each being adapted to select a disengaged outgoing line UL. According to the invention these searchers are also arranged to control the marking of the calling lines in the connecting apparatus AK, so that the calling line will be marked only in that connecting apparatus which belongs to the outgoing line selected by the searcher, for the purpose of preventing double connections, when several calls occur simultaneously. If there were no such control double connections could occur for instance by two simultaneously calling incoming lines being connected to the same outgoing line in the same connecting apparatus or by two outgoing lines being connected to the same incoming line in different connecting apparatus. This is now prevented by putting the circuits, whereby the lines are marked in the connecting apparatus, under the control of the searchers, so that they may be switched by the latter to any one of the connecting apparatus. As shown in Fig. 1, each searcher is arranged to control a separate group of marking circuits MS₁, MS₂, by means of relays GR₁, GR₂ or the like, through which each group of circuits can be switched on to any of the connecting apparatus AK.

Each group of marking circuits is further put under the control of a call sequence controller, OK_1 and OK_2 respectively, consisting of relays adapted to control said circuits for the purpose of marking the calling line in question, said controllers being also arranged to effect such a control of the circuits as to prevent a simultaneous marking of more than one calling line in each group MS_1 or MS_2 so that, in case several calls occur simultaneously, the calls will be marked one after the other according as the searcher becomes available for another call.

The switching operation proceeds principally in the following manner. On a call occurring on one of the incoming lines, one of the searchers S is immediately operated to select a disengaged outgoing line and to connect the appertaining group of marking circuits MS to the connecting apparatus AK corresponding to the line selected, by operating the corresponding relay GR . At the same time the calling line has been marked by the corresponding call sequence controller OK and the connecting apparatus will therefore be operated in such a manner that the outgoing line selected is connected to the incoming line in question. In case two calls should occur simultaneously the two searchers are operated each by one calling line and the searchers will therefore be operated simultaneously. Supposing the searchers then select different outgoing lines, the calling lines will be marked in the different connecting apparatus corresponding to the different selected outgoing lines, as described, and consequently, they will obtain connection each with a separate outgoing line. If, on the other hand, the searchers should be operated exactly at the same moment so as to select the same outgoing line, the searchers would also operate the corresponding relays GR_1 and GR_2 at the same time. In order to prevent a double connection in such a case the two relays GR_1 , GR_2 of each pair of relays corresponding to each particular connecting apparatus AK are so combined with one another that, in case they are operated simultaneously, only one of them can be brought into operation. The two calling lines will therefore obtain connection one after the other. As soon as one of the calling lines has been connected to the outgoing line in question, the latter will be marked as engaged and the second searcher will then immediately search for the next disengaged line and effect the connection of this line with the second calling line.

In order to reduce the probability of the searchers selecting the same line, the searchers may be connected so as to select the outgoing lines in a different order of sequence, as shown in Fig. 2, wherein the outgoing

lines are connected to the searchers in a reversed order of sequence, so that the searcher S_1 selects the lines in the order UL_1 , UL_2 , UL_3 , whereas the searcher S_2 selects the lines in the order UL_3 , UL_2 , UL_1 . It is readily seen, that the case above referred to, when both searchers select the same line, can occur in the arrangement according to Fig. 2 only in the rare case when the searchers are operated simultaneously, while all outgoing lines except one are engaged.

According to Fig. 2 the incoming lines are further divided into two groups G_1 , G_2 , provided each with a separate searcher S_1 and S_2 respectively, so that the lines of the group G_1 are capable of operating only the searcher S_1 , whereas the searcher S_2 can be operated only by the lines of the group G_2 . This arrangement has the advantage that the wiring of the searchers S and the call sequence controllers OK is simplified and, in addition thereto, the possibility of a complete blocking of the switching division is further reduced.

Fig. 3 shows the arrangement according to Fig. 2 applied to switching divisions having more than two searchers. The searchers are then likewise connected so as to select the outgoing lines in a different order of sequence, but the lines UL are screwed in respect of their connection to the searchers, as shown in the drawing. The arrangement according to Figure 3 is obviously not so good as that of Figure 2, as, although the possibility of two searchers landing on the same UL line is reduced it is not eliminated if the first two lines over which the searchers search should be busy.

The invention is primarily suitable for the preselecting and group selecting stages of automatic and semi-automatic telephone exchanges, but it may generally be applied to switching systems of all kinds where connection is to be established with any one of a number of switching apparatus or the like, for instance number registers, operators' positions etc., which are accessible in common to a plurality of lines.

Figs. 4 and 4^A show two groups G_1 , G_2 of incoming lines IL and two outgoing lines UL_1 , UL_2 with appertaining connecting apparatus AK_1 , AK_2 .

A suitable type of connecting apparatus consists of a number of marking relays MR and a number of connecting relays AR , adapted to be operated two by two in different combinations. The sets of contacts KG are arranged in intersecting (horizontal and vertical) rows, one marking relay MR being provided for each vertical row and one connecting relay AR for each horizontal row. The arrangement is such that the set of contacts KG desired will be operated by energizing the relays MR , AR of the corresponding vertical and horizontal rows.

The set of contacts KG_{12} , for instance, is operated by energizing the relays MR_2 and AR_2 .

The sets of contacts KG of each apparatus

- 5 AK are connected partly parallelly with the corresponding outgoing line UL and partly with the different incoming lines IL . In the example shown each group G_1 and G_2 respectively of incoming lines comprises the 10 lines connected to two vertical rows. The lines connected to the different vertical rows form sub-groups UG_1 , UG_2 . Each connecting apparatus comprises 100 sets of contacts arranged in ten rows. Thus, each sub-group 15 UG would comprise ten lines but other ways of grouping the lines and the sets of contacts are, obviously, possible.

Assigned to each group G_1 and G_2 , respectively is a call sequence controller, which 20 consists in this case of a number of relays BR corresponding to the different vertical rows or sub-groups UG , and a number of relays CR corresponding to the different lines of each vertical row or sub-group UG .

25 Fig. 5 shows the searchers S_1 and S_2 belonging to the line groups G_1 and G_2 as well as the relays GR by means of which the marking circuits MS_1 and MS_2 are switched on to the different connecting apparatus AK .

30 The switching operation is as follows:—

Upon a call for instance on the line IL_1 , a circuit 1 is closed through a relay LR_1 , which then closes a circuit 2 through the relay BR_1 of the corresponding sub-group 35 UG_1 . The relay last mentioned then energizes and connects itself into a holding circuit 3 carried over a back contact of the relay BR_2 and including the relay DR_1 , which, upon energizing, closes a circuit 4 through the relay CR_1 corresponding to the line IL_1 . The latter relay then connects itself into a holding circuit including the relay DR_1 . A call occurring later in the sub-group UG , cannot disturb the switching operation thus 40 started, as the circuit of the relay BR_2 is open at the relay DR_1 , and consequently, said call cannot be effective until the first switching operation is completed. In case calls should occur in both sub-groups UG_1 , 45 and UG_2 , so that the relays BR_1 and BR_2 are operated simultaneously, the relay BR_2 would open the holding circuit of the relay BR_1 and, consequently, even in this case only one of the calls would be effective, while the other will have no effect, until the operation 50 started has been completed. In case two or more calls should occur simultaneously within the same sub-group, only one of the relays CR would be brought into operation or 55 retained in operated position, owing to the relays CR controlling mutually their holding circuits similarly to the relays BR . The effect of the relays BR and CR is therefore that, in case of several calls occurring simultaneously within the group G in question,

only one of the calling lines will be marked as calling and obtain connection, while the other will have to wait, until the line first marked has obtained connection, when one of the waiting lines is immediately marked 70 in a similar way.

Upon the energizing of the relay DR_1 , a circuit 6 was completed which, on the superposition of the first outgoing line UL_1 being disengaged, is closed through the first relay 75 SR_1 of the searcher S_1 . The relay last mentioned now closes a circuit 7 through the relay G_1R_1 which then switches the marking circuits MS_1 on to the operating apparatus AK_1 at the same time connecting itself into a holding circuit containing a relay HR_1 , which by opening a contact h prevents a subsequent energizing of the relay G_1R_2 , for the purpose of obviating disturbances by 80 calls from the group G_2 . Similarly upon a call in the group G_2 the relay G_1R_2 would prevent disturbance by calls from the group G_1 by cutting in the relay HR_1 . If, on account of simultaneous calls from both groups G_1 and G_2 , both relays G_1R_1 and G_1R_2 85 should be cut in simultaneously, only the relay G_1R_2 would remain operated, as this relay opens the holding circuit of the relay G_1R_1 . In this way a simultaneous marking of a plurality of calling lines in the same 90 connecting apparatus is prevented in case of the searcher selecting the same outgoing line.

Upon the marking circuits MS_1 being switched on to the connecting apparatus a circuit 8 is closed through the marking relay MR_1 , which then closes a circuit 9 through the operating winding AL of the connecting relay AR_2 . The relay last mentioned, upon energizing, operates the sets of contacts KG_1 , whereby the line IL_1 is connected to the line UL_1 . At the same time a holding circuit 10 is closed through the holding winding HL of the relay AR_3 and a cut-off relay UL_1 . The latter relay cuts off the relay LR_1 , thereby causing a successive de-energizing of the 100 relays used for the switching operation, except the connecting relay AR_3 , which maintains the connection, until the connection is severed at the end of the conversation. Upon the operation of the relay AR_3 , a circuit 11 is closed through a relay FR_1 , whereby the line UL_1 is marked as engaged. 105

What I claim is:—

1. In a telephone system, the combination with a group of lines and a group of 120 switches, each switch being adapted to connect to any one of the lines, of a plurality of devices common to the group of switches and adapted to mark a calling line in only one of the switches and to mark that switch in which the line is so marked. 125

2. In a telephone system, the combination with two groups of lines and a group of switches, each switch being adapted to connect to any one of the lines of either group, 130

- of a plurality of devices adapted, when a line in each group calls simultaneously, to mark two simultaneously calling lines in two different switches and to mark those two switches individually to the two lines.
3. In a telephone system, the combination with a group of lines and a group of switches, each switch being adapted to connect to any one of the lines, of a plurality of devices, each consisting of a master switch adapted to mark a switch as the one to connect to a calling line and of a sequence controller adapted to mark only one line as calling in the switch so marked.
4. In a telephone system, the combination with a group of lines and a group of switches, each switch being adapted to connect to any one of the lines, of a plurality of devices, each consisting of a master switch adapted to mark a switch as the one to connect to a calling line, a sequence controller adapted to mark only one line as calling in the switch so marked and means for temporarily preventing the sequence controller from marking if two master switches are marking the same switch of the group and thereafter for permitting the master switch associated with the sequence controller which was temporarily prevented from marking to mark another switch of the group.
5. In a telephone system, the combination with a group of lines and a group of

switches, each switch being adapted to connect to any one of the lines, of a plurality of devices, each consisting of a master switch, each of the master switches being adapted to choose in a different order of sequence one of the switches of the group and to mark that one as the one to connect to a calling line, a sequence controller adapted to mark only one line as calling in the switch so marked and means for temporarily preventing the sequence controller from marking if two master switches are marking the same switch of the group and thereafter for permitting the master switch associated with the sequence controller which was temporarily prevented from marking to mark another switch of the group.

6. The combination with a group of lines divided into sub-groups and a group of switches adapted to connect to any line of the group, of a plurality of devices, each device consisting of a master switch adapted to mark any idle switch of the group as the one to connect to a calling line and of a sequence controller associated with one of the sub-groups and adapted to mark only one line as a calling line in the switch marked by the master switch.

In testimony that I claim the foregoing as my invention I have signed my name this 2nd day of February 1923.

GOTTHILF ANSGARIUS BETULANDER.
